UNITED STATES PATENT OFFICE

CHARLES W. HOBART, OF BOSTON, MASSACHUSETTS

GARMENT SUPPORTER

Application filed May 22, 1930. Serial No. 454,638.

This invention relates to garters or hose supporters, and has particular reference to the means for connecting the same to the tops of hose or stockings, said means consisting of 5 a button-carrying member and a loop or clasp to be engaged with or dis-connected from the button.

One of the objects of the invention is to provide an economical and easily operable 10 structure of the hose-connecting members, and another object is to provide a structure which will be comfortable in use.

With said objects in view, the invention consists in the construction and combination 15 of parts substantially as hereinafter described and claimed.

Of the accompanying drawings:

Figure 1 is an elevation of a complete garter constructed according to my invention. 20 Figure 2 represents a section on line 2—2 of Figure 1.

Figures 3 and 4 are views similar to a portion of Figure 1, but illustrating the connecting members in different relative positions 25 which they occupy during manipulation.

Similar reference characters designate similar parts or features in all of the views.

In Figure 1 an ordinary leg-surrounding band is illustrated at 12 and having a suitable pad 13 which is usually of two-ply material as indicated in Figure 2. Secured to 30 and depending from the pad 13 is a flexible strip 14 of elastic material capable of stretching under tension.

A substantially rigid or stiff strip 15, of 35 metal, celluloid, hard rubber, or suitable equivalent thereof, has a slot 16 near its upper end and is bent above said slot to provide a lug 17, and near its lower end has a stud or button 18 of ordinary or preferred form.

The elastic strip 14, at an intermediate point of its length, is doubled and passes through the slot 16 in the stiff strip 15 to provide an elastic loop in which the loop-shaped clasp 19 is hung, said clasp having a 45 bent lower end portion to provide a lug 20.

The portion of the elastic strip 14, below its loop which extends through the slot 16 of the stiff strip 15, extends down along the 50 back of the said stiff strip and over the lower

tip edge of the latter, and is secured at 21 as by doubling and bending the ends of the strips 14, 15, together (Fig. 2).

In operation, connection is made with a stocking in practically the usual way, but 55 such connection is facilitated as will now be explained. By pressure against the lugs 17, 20, apart from each other, the relative positions of the clasp member 19 and the strip 15 with its button 18, are shifted as 60 illustrated by comparing Figures 3 and 4, and after the stocking top has been engaged with the button and the clasp member fitted down over it, the elastic loop in which the clasp member is hung exerts a pull and aids 65 in drawing the clasp member up to the position shown in Figures 1 and 2, and holds the members reliably in stocking-gripping relationship. And of course the above-described 70 relative movements of the members 15, 19, by pressure against their lugs, enable disconnection of the stocking to be quickly effected.

The elastic strip 14 has several advantageous characteristics, viz: its portion above the slot 16 provides an elastic connection with 75 the pad 13 or any equivalent thereof and therefore tends to aid in comfort to the wearer, its elastic loop in which the clasp member 19 is hung yieldingly holds the clasp 80 member and button in operative relationship as above described, and its lower portion provides a backing for the stiff strip 15 and protects the skin of a wearer, or an undergarment, from injury or wear due to said stiff strip. As said strip 14 is a single piece of 85 material, the cost of production of the entire article is materially less than if separate pieces were secured together for the same or similar purposes.

Owing to the fact that the stiff strip 15 90 has a forwardly projecting lug 17 at its upper end, above the slot 16, while the clasp member 19 has a forwardly projecting lug at its lower end, the device may be operated by one hand either when connecting it to a garment 95 or disconnecting it therefrom. By forcing or pressing the lugs 17 and 21 toward each other after a garment has been laid over the stud or button 18, strong and positive connection with the garment is obtained. On 100

the other hand, separation of a garment from the device is easily effected by simply pressing the lug 20 and the bent lower end 21 of the stiff plate or member toward each other.

5 While the invention is illustrated as a man's garter, with the usual band to surround the leg of the wearer, it is to be understood that I do not limit myself thereto, as the described members of my invention may be employed in hose supporters such as those 10 used by women.

Having now described my invention, I claim:—

15 1. A garment supporter having garment-connecting members comprising a strip of stiff material having a button, said strip being provided with a slot and having a forwardly projecting lug at its upper end, a strip of elastic material a loop portion of which 20 extends through said slot, and a clasp member hung at one end in said loop portion of the elastic strip and having its lower end arranged to engage said button, said clasp member having a forwardly projecting lug at its lower end.

25 2. A garment supporter having garment-connecting members comprising a strip of stiff material having a button near one end and a forwardly projecting lug at the other end and provided with a slot near said lug, a strip of elastic material having a loop portion extending through said slot and extending over the back of the stiff strip, and a 30 clasp member hung at one end in the loop of the elastic strip and engageable with said button and having a forwardly projecting lug at its lower end.

In testimony whereof I have affixed my signature:

CHARLES W. HOBART.
